(57) **CLAIM**

The ornamental design for a water bottle, as shown and described.

DESCRIPTION

FIG. 1 is a top, front perspective view of a water bottle showing our new design;

FIG. 2 is a front view of FIG. 1, with the back view being the mirror image thereof;

FIG. 3 is a right side view of FIG. 1, with the left side view being the mirror image thereof;

FIG. 4 is a top view of FIG. 1; and,

FIG. 5 is a bottom view of FIG. 1.

The broken line showing of the bottle top in FIG. 1 is for illustrative purposes only and forms no part of the claimed design.
